EX

OR D 4,011

Design for Trade Mark.

4011

R. W. Bell.

PATENTED MAY 10 1870

Buffalo, N.Y.

United States Patent Office.

ROBERT W. BELL, OF BUFFALO, NEW YORK.

Design No. 4,011, dated May 10, 1870.

DESIGN FOR A TRADE-MARK.

The Schedule referred to in these Letters Patent and making part of the same.

I, ROBERT W. BELL, of the city of Buffalo, in the county of Erie and State of New York, have invented and produced a new and original Design for a Trade-Mark, of which the following is a specification.

My design, as represented in the accompanying drawing, consists of the picture of a buffalo, with the word "soap" engraved or marked thereon, and is devised as a trade-mark for R. W. BELL & Co., manufacturers of soap at the aforesaid city of Buffalo, the picture of the animal symbolizing the place of manufacture, while the letters marked on the picture designate the article manufactured.

The word "soap" may be engraved in various ways and on different portions of the body, although it is

preferably displayed on the body of the animal, where it will be conspicuous, as shown in the drawing.

The design can be stamped directly on the bar of soap, or be embossed or printed on the envelope containing the same, or on circulars or other papers, as required.

Claim.

I claim as my invention—

The design for a trade-mark, as hereinbefore described and shown.

R. W. BELL.
